A. J. HALL,
CONTROL APPARATUS,
APPLICATION FILED NOV. 25, 1914.

1,300,383.

Patented Apr. 15, 1919.

UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,300,383.

Specification of Letters Patent. Patented Apr. 15, 1919.

Application filed November 25, 1914. Serial No. 873,919.

To all whom it may concern:

Be it known that I, ARTHUR J. HALL, a subject of the King of Great Britain, and a resident of Wilkinsburg, in the county of 5 Allegheny and State of Pennsylvania, have invented a new and useful Improvement in Control Apparatus, of which the following is a specification.

My invention relates to control apparatus 10 for governing the operation of dynamo-electric machines, and it has special reference to liquid rheostats that are adapted for use in connection with alternating current induction motors.

One of the objects of my invention is to 15 simplify and improve the construction and operation of apparatus of the above-indicated character and to provide control apparatus of simple, compact and light construction which shall operate effectively and 20 reliably to perform its intended functions.

Another object of my invention is to provide a combined discharge and regulating 25 valve for liquid rheostats having a minimum number of movable parts and which may be actuated readily without undue frictional resistance.

A still further object of my invention is 30 to provide a fluid-pressure operating mechanism for effecting the actuation of the combined discharge and regulating valve hereinbefore referred to, and which shall embody a plurality of electrically operated inlet and exhaust valves associated with each 35 end of the operating cylinder by means of which the discharge valve may be actuated at different rates of speed.

In a co-pending application, Serial No. 829,432, filed April 4, 1914, by G. M. Eaton 40 and assigned to the Westinghouse Electric & Manufacturing Company, a liquid rheostat is disclosed which is provided with independently operated discharge and regulating valves that are arranged in concentric or 45 telescopic relation. For certain classes of work, the operation of valves of this type is sluggish and unreliable by reason of the excessive amount of frictional resistance that the moving parts encounter. Moreover, 50 there is an appreciable time interval between the manipulation of the controller which governs the operation of the valves and the initial movement thereof, so that the operation is not as sensitive and quickly responsive as may be desired in certain service.

According to my present invention, I propose to overcome the difficulties and disadvantages of operation of the prior art and to provide a device by means of which the benefits and objects hereinbefore mentioned 60 may be secured.

In the accompanying drawing, Figure 1 is a view, partially in section and partially in side elevation, of a portion of a pair of liquid rheostats constructed in accordance 65 with my invention; Fig. 2 is a plan view of the apparatus shown in Fig. 1; Fig. 3 is an enlarged plan view of the combined discharge and regulating valve constituting a part of the apparatus illustrated in Figs. 1 70 and 2; and Figs. 4 and 5 are sectional views showing said valve in different operating positions.

Referring to the drawing, the apparatus shown comprises a main receiving tank or 75 reservoir 1, a plurality of liquid rheostats 2 and 3 disposed above said tank and severally having combined discharge and regulating valves 4, and a fluid-pressure operating mechanism 5 for actuating said valves con- 80 currently.

The main reservoir 1 and the several liquid rheostats 2 and 3, which are of like construction, may be of any suitable type. Each of the rheostats 2 and 3 is provided with a bottom opening 7 which communicates with the reservoir 1, and an inlet port 8 is associated with each rheostat for the purpose of continuously supplying electrolyte thereto.

Within the discharge opening 7, the combined discharge and regulating valve 4 is located and said valve comprises an annular supporting member 8 having a plurality of seats 9 and 10 of different diameters and a plurality of tubular sections 11 and 12 that 90 respectively fit tightly over said seats 9 and 10 and are suitably secured thereto. The tubular sections 11 and 12 are concentrically related and project in opposite directions from the annular supporting member 8, the 95 lower section 12 being substantially of the diameter of the discharge opening 7 and adapted to have a sliding engagement with the edge thereof, and the upper section 11 being of materially less diameter, so that 100 when the valve 4 occupies its initial position, as shown in Fig. 1, an annular opening is provided between the section 11 and the edge of the opening 7, through which the inflowing electrolyte is discharged. By reason of 110

the comparatively slight and restricted area of contact between the tubular section 12 and the edge of the opening 7, there is no appreciable frictional resistance to the movement of the tubular discharge and regulating valve 4 and no tendency to bind is developed.

- 10 The lower tubular section 12 is provided with a plurality of longitudinally projecting guide members 13 which are preferably integral therewith and which project upwardly into engagement with the edge of the opening 7 for the purpose of guiding the valve 4 in its initial upward movement.
- 15 The annular member 8 is provided with a plurality of radial arms 14 and a central portion 15 to which is secured an operating rod 16 by means of which the valve 4 is supported and actuated, as will be herein-
20 after set forth.

- 25 The fluid-pressure operating mechanism 5 comprises a cylinder 20 having a plurality of movable pistons 21 and 22 contained therein and mechanically associated through the agency of a piston rod 23. A cross arm 24 has a bearing 25 upon the cylinder 20 and is rigidly associated with the piston rod 23 in a suitable manner and is adapted to be actuated thereby. The supporting rods 30 16 that carry the several valves 4 of the rheostats 2 and 3 are attached to the respective ends of the cross arm 24.

- 35 A combined inlet and exhaust valve 30 and an auxiliary exhaust valve 31 are associated with the lower end of the cylinder 20 and said valves are provided with operating electromagnets 32 in accordance with well-known practice. The upper end of the cylinder 20 is provided with a combined 40 inlet and exhaust valve 33 and an auxiliary exhaust valve 34, both of which are adapted for electromagnetic operation. Without describing the construction of these valves in detail, it is deemed sufficient to state that, 45 in their normal deenergized positions, an inlet port 36 of valve 30 is closed, while its exhaust port 37 and an exhaust port 38 of valve 31 are open to establish communications with the atmosphere. Moreover, an inlet port 39 of valve 33 is open to admit 50 operating fluid to the upper end of the cylinder 20, while its exhaust port 40 and an exhaust port 41 of valve 34 are closed.

- 55 The upper end of the cylinder 20 is also provided with a pressure-responsive device 43 which comprises a cylinder 44, a movable piston 45 and a spring 46 which surrounds a stem 47 and acts in opposition to the pressure within the upper end of cylinder 20. 60 The stem 47 is provided with a switch member 48 which is adapted to cooperatively engage a plurality of stationary contact terminals 49 under predetermined pressure conditions. The purpose of the fluid-pressure 65 responsive device 43 and the circuit connec-

tions and mode of operation of the several valves 30, 31, 33 and 34 are fully set forth in my co-pending application, Serial No. 876,484, Dec. 10, 1914, and, since these features pertain only indirectly to my present 70 invention, no description thereof will be given.

Assuming the various parts of the apparatus to occupy the positions shown in Fig. 1, it is evident that operating fluid is admitted through inlet port 39 of the valve 33 to the upper end of the cylinder 20, while the lower end thereof is opened to the atmosphere through exhaust ports 37 and 38 of the valves 30 and 31, respectively. Under 75 these conditions, an unbalanced pressure acts upon the associated pistons 21 and 22 and said pistons are forced to their lowermost positions, whereby the several combined discharge and regulating valves 4 are 80 also caused to occupy similar positions. The inflowing electrolyte, therefore, is permitted to be discharged into the main reservoir 1 through the annular discharge openings 7.

In order to quickly close the discharge 90 openings, all of the valves 30, 31, 33 and 34 are energized and moved into their opposite positions, whereby the supply of operating fluid to the upper end of the cylinder 20 is cut off, while both of the exhaust ports 95 40 and 41 of the respective valves 43 and 44 are opened to permit the escape of fluid to the atmosphere. Simultaneously, the exhaust ports 37 and 38 of the valves 30 and 31 are closed and fluid pressure is admitted 100 to the lower end of the cylinder 20 through the inlet port 36 of valve 30.

By reason of the opening of exhaust ports 105 40 and 41, the operating fluid in the upper end of the cylinder 20 is permitted to rapidly escape, thereby reducing the pressure thereof and permitting a relatively rapid upward movement of the pistons 21 and 22, and, hence, of the regulating valves 4.

When the combined discharge and regulating valves 4 reach the position shown in Fig. 4, the discharge openings 7 are closed, and the continuously inflowing electrolyte then rises to a height corresponding to the upper end of the tubular section 11 of the valves 4, which height is termed the "flush-level" and is just sufficient to immerse the lower ends of the electrodes 50. The "flush-level", therefore, is quickly established by reason of the sensitiveness and rapidity of movement of the operating mechanism 5.

Having established the "flush-level", it is desirable to effect further movements of the valves 4 at a comparatively slow rate, 125 whereby the height of the electrolyte within the rheostats 2 and 3 may be regulated as desired, it being understood, of course, that any excess of electrolyte overflows and is discharged through the valves 4. The slow 130

rate of movement is obtained by causing the valve 34 to effect the closure of its exhaust port 41, thus retarding the escape of operating fluid from the upper end of the cylinder 20.

As the regulating valves 4 are raised beyond the "flush-level" position to a position such as indicated in Fig. 5, the discharge openings 7 are maintained closed by reason of the substantially tight fit between the lower sections 12 of the valves 4 and the edge of the openings 7, while the level of the electrolyte is raised to a height corresponding to that of the upper ends of sections 11 of valves 4.

Obviously, the upward movement of the valves may be arrested at any point by opening the inlet port 39 of valve 33 and closing the exhaust port 41 of valve 34 and exhaust port 40 of valve 33, whereby balanced pressure conditions acting upon the pistons 21 and 22 are obtained.

By suitably operating the valves 30, 31, 33 and 34, the pistons 21 and 22 and their associated valves 4 may be actuated in a downward direction at different rates of speed. For instance, when it is desired to quickly discharge the electrolyte from the rheostats 2 and 3, it is only necessary to permit the several control valves just referred to, to be deenergized and to be moved into their initial positions, as shown in Fig. 1. Operating fluid is then admitted to the upper end of the cylinder 20 and released from the lower end thereof, whereby the unbalanced pressures effect the desired result and the valves 4 are quickly lowered to their initial positions to permit the discharge of electrolyte through said valves and through the annular openings 7 between said valves and the respective rheostat tanks.

Modifications in the structural details and in the arrangement and location of parts may, of course, be effected without departing from the spirit and scope of my invention, and such modifications are intended to be covered in the appended claims.

I claim as my invention:

1. The combination with a liquid-containing tank having a bottom opening therein, of a hollow member open at its ends and comprising a plurality of cylindrical sections of materially different diameters, the larger section being located at the bottom and adapted to substantially fill said opening.

2. The combination with a liquid-containing tank having a bottom opening therein, of a hollow member open at its ends and comprising an upper cylindrical section of materially less diameter than said opening and normally adapted to project therethrough, and a lower cylindrical section of substantially the diameter of said opening, said lower section being longitudinally dis-

posed below said opening and adapted to substantially fill said opening when raised in position.

3. The combination with a liquid-containing tank having a bottom opening therein, of a movable valve comprising two hollow cylindrical portions open at the ends, the upper portion normally projecting through said opening and providing an annular opening of material size between the edge of said bottom opening and said upper portion, and the bottom portion normally located below said opening and being of substantially the same diameter and adapted to fill said opening when said movable valve is raised in position.

4. The combination with a liquid-containing tank having a bottom opening therein, and means for supplying liquid thereto, of a tubular valve member disposed in said opening and normally adapted to permit the discharge of liquid therethrough, said valve member being adapted to close said opening when raised to a predetermined height and to fix the height of the liquid within said tank when raised above said predetermined height.

5. The combination with a liquid-containing tank having a bottom opening therein and means for continuously supplying liquid thereto, of a tubular valve open at its ends and disposed in said opening and initially occupying its lowest position to permit the discharge of liquid between it and the edge of said opening, said valve being adapted to be raised to close said opening and to regulate the height of the liquid within said tank.

6. A tubular valve for a liquid-containing tank comprising an annular supporting member having portions of different diameters, a plurality of tubular members of corresponding diameters and open at the ends to be fitted over said respective portions and secured thereto, and means associated with said annular member for supporting said valve.

7. A tubular valve for a liquid-containing tank comprising an annular supporting member having portions of different diameters, and a plurality of tubular members open at the ends and fitting tightly over said respective portions and projecting in opposite directions, and longitudinally projecting extensions associated with the inner end of the tubular member of large diameter.

8. The combination with a liquid-containing tank having a bottom opening therein, of a hollow member open at its ends and comprising a plurality of cylindrical portions of materially different sectional areas, the portion of larger area being disposed at the bottom free from said opening and adapted to substantially fill said opening under predetermined conditions.

9. The combination with a liquid-contain-

ing tank having a bottom opening therein, of a hollow member open at its ends and comprising an upper cylindrical portion of materially less sectional area than said opening and normally adapted to project upwardly therethrough and a lower cylindrical portion of substantially the area and configuration of said opening and normally disposed below and free from said opening and 10 adapted to substantially fill it when raised in position.

10. The combination with a liquid-containing tank having a bottom opening therein, and means for supplying liquid thereto, 15 of a hollow valve open at its ends and comprising an upper cylindrical portion of materially less sectional area than said opening

and normally adapted to project upwardly therethrough to permit the free discharge of liquid between it and the edge of said opening and a lower cylindrical portion of substantially the area and configuration of said opening and adapted to be raised into sliding engagement with the edge of the opening to cause the complete discharge of said liquid 25 downwardly through both portions of said valve.

In testimony whereof, I have hereunto subscribed my name this 18th day of Nov. 1914.

ARTHUR J. HALL.
